OTTO P. SCHUSTER, OF IRWIN, PENNSYLVANIA, ASSIGNOR TO WESTINGHOUSE ELECTRIC & MANUFACTURING COMPANY, A CORPORATION OF PENNSYLVANIA

CONTROLLER DRUM

Application filed March 19, 1929. Serial No. 348,348.

This invention relates generally to controllers and more particularly to controller drums.

The object of the invention, generally stated, is the provision of a controller drum that shall be simple in construction and readily and economically manufactured and assembled.

A more specific object of the invention is to facilitate the assembling of a controller drum and the arrangement of the contact segments to give the desired contact surfaces.

It is also an object of the invention to facilitate the rearrangement of the elements of a controller drum to locate the contact segments in predetermined positions to meet the operating conditions and to obtain the maximum length of service.

Other objects of the invention will, in part, be obvious and, in part, appear hereinafter.

The invention, accordingly, is disclosed in the accompanying drawings and comprises the features of construction, combination of elements and arrangement of parts which will be exemplified in the structure herein-after set forth, and the scope of the application of which will be indicated in the claims.

For a fuller understanding of the object of the invention, reference may be had to the following detailed description, taken in connection with the accompanying drawings, in which;

Figure 1 is a view, partly in section and partly in side elevation, of a controller drum constructed in accordance with the invention.

Fig. 2 is a horizontal section, taken along the line II—II Fig. 1, showing a top plan view of the contact members and support plates.

Fig. 3 is a horizontal section, taken along the line III—III Fig. 1, showing a top plan view of contact members similar to those shown in Fig. 2 but reversed.

Fig. 4 is a horizontal section, taken along the line IV—IV Fig. 1, showing a top plan view of the contact members and support plates similar to Fig. 2 but illustrating how the contact members may be shaped to meet desired operating conditions, and

Fig. 5 is a top plan view of a contact member blank.

Referring to the drawing, 10 designates a drum shaft which is shown mounted in a ball bearing illustrated generally at 11. The drum shaft may be mounted in any suitable controller casing in any well known manner.

In this particular construction, an insulating sleeve 12 is mounted on the drum shaft for the purpose of insulating the shaft from the other members of the controller. As shown, annular support plates 13 are mounted upon the insulating sleeve 12 and each plate is provided with a plurality of holes 14 disposed in a circle concentric with the axis of the shaft 10.

In order to retain the rings spaced from one another and located in the desired positions, spacing rings 15 are provided. As will be readily understood, the spacing rings 15 may be made of any desired length, depending on the distance apart that it is desired to space the support plates and drum segments, to be referred to hereinafter. The spacing rings may be made from any suitable insulating material well known in the art and may serve not only to space the support plates but also to insulate them from one another.

The contact members 16 are mounted on the support plates 13. In this particular embodiment of the invention, each contact member comprises a contact segment 17 and a flange 18. As shown, the flange is provided with holes 19 which may be disposed to register with openings 14 in the support plates. In this instance, the flanges of the contact members 16 are secured to the support plates by means of bolts 20.

Since the support plates are severally provided with a plurality of holes 14, the contact members may be moved circumferentially about the shaft to set them in any predetermined position. This facilitates the arrangement of the contact segments to provide the desired contacting surface.

It will be noted that the flange 18 is so positioned relative to the contact segment 17 that the latter stands symmetrical with reference to a horizontal central plane taken

through the support plate 13, when the flange is disposed above the support plate, with the contact segment extending downwardly, and also when the flange is located below the support plate, with the contact segment extending upwardly. Therefore, a contact member of this type may be reversed to present the same contact face in the same position.

- Ordinarily, in the operation of controllers 10 the circuits are interrupted when the drum is rotated in one direction and established when it is actuated in the opposite direction. Therefore, the arcs drawn during circuit-interrupting operations are always broken 15 at the same ends of the contact members. This results in the burning of one end of a contact member more quickly than the other. Consequently, a contact member that may be reversed without changing its location is 20 highly desirable since, when one end is burned, it may be turned to present an undamaged end for contacting purposes and thereby double the life of the contact member.
- 25 It is also pointed out that, in reversible contact members of this type, when both ends of a segment are damaged, they may be cut off to provide a contact member of smaller size that may be utilized to replace smaller 30 contact members. Therefore, a reversible contact member not only gives maximum life but lends itself to remodeling.

In constructing the contact members, they 35 may be made in the form of rings and then cut to obtain contact members of the desired size. Further, contact members may be inserted at any time to replace damaged segments or to change the contact surface of the drum.

- 40 In conclusion, it is pointed out that, while the illustrated example constitutes a practical embodiment of my invention, I do not limit myself to the exact details shown, since modifications of the same may be considerably 45 varied without departing from the spirit of the invention, as defined in the appended claims.

I claim as my invention:

1. In a contact drum, in combination, a 50 shaft, an insulating sleeve mounted on the shaft, support plates mounted on the shaft and insulated therefrom by the sleeve, spacing members interposed between the support plates, contact members having inwardly extending flanges disposed to be connected to the support members, and a contact plate extending transversely of the flanges, said contact plate being disposed symmetrically with reference to a central horizontal plane extending through the support plates.
2. In a contact drum, in combination, a 55 shaft, an insulating sleeve mounted on the shaft, annular support plates mounted on the sleeve, said plates being provided with openings, spacing rings interposed between

the support plates, contact members having inwardly extending flanges for attachment to the support plates, a contact segment extending at substantially right angles to the flanges, and means for attaching the flanges 70 to the support plates.

3. In a reversible contact drum, in combination, a shaft, an insulating sleeve mounted on the shaft, annular support plates mounted on the sleeve, said support plates having a 75 plurality of openings therein arranged in a circle, insulating rings interposed between the support plates to space them in a predetermined manner, contact members provided with inwardly extending flanges adapted to 80 be seated on the support plates, and contact segments carried by the flanges, said flanges being provided with openings disposed to register with the openings in the support plates, and means for engaging in the openings in the flanges and support plates to 85 mount the contact members in position on the shaft, the contact segments being disposed relative to the flanges to stand symmetrically with reference to a central horizontal plane 90 extending through the support plates.

4. In a contact drum, in combination, an insulated support, a contact ring adapted to be cut into sections to provide a plurality of contact members of a predetermined angular 95 extent, each comprising an inwardly extending flange, and a contact segment carried by the flange and disposed relative to it to permit reversal of the contact member on the support without changing the position of the contact segment, and means for attaching the flange to the support in different predetermined positions.

5. In a controller drum, in combination, a 100 shaft, support plates carried by the shaft and extending outwardly, contact members comprising flanges and contact segments carried by the flanges adapted to be mounted on the support plates, the support plates and contact segments being so designed that the 105 contact segments stand symmetrically relative to central planes through the support plates when the flanges are mounted either above or below the support plates, thereby 110 providing for reversal of the contact members.

In testimony whereof, I have hereunto subscribed my name this 12th day of March, 1929.
